INVENTOR

Arthur H. Robinson

By Oskar Billemau ATTY.

UNITED STATES PATENT OFFICE.

ARTHUR H. ROBINSON, OF LAKWOOD, OHIO:

HEATING APPARATUS.

Application filed August 30, 1923. Serial No. 660,163.

To all whom it may concern:

Be it known that I, ARTHUR H. ROBINSON, a citizen of the United States, residing at Lakewood, in the county of Cuyahoga and State of Ohio, have invented certain new and useful Improvements in Heating Apparatus, of which the following is a specification.

My invention relates to improvements in heating apparatus, and more particularly to improved means for positively and mechanically circulating and distributing hot air in connection with heating units or systems, thereby producing what are known as "forced draughts".

The primary object of the invention is to provide a generally improved heating apparatus or system of the type or class indicated which will be simple in construction, cheap of manufacture and efficient in use.

A further and very important object is the provision of an improved form and arrangement of hot air accumulating and distributing chamber and pipes or conduits adapted to be readily installed or connected to heating units and systems already installed as well as to form a component part of a new hot air heating system.

A further and important object is the provision of an improved form and arrangement of mechanical air circulating device of the motor driven blower type and in which the motor is mounted exterior to the hot air accumulating and distributing chamber or manifold.

A still further object is the provision of a motor driven mechanical air circulating device which will not in any way interfere with the ordinary operation of the furnace or heating system when the device is at rest or out of operation.

With the above mentioned and other ends in view the invention consists in the novel construction, arrangement and combination of parts, hereinafter described, illustrated in some of its embodiments in the accompanying drawings and particularly pointed out in the appended claims.

Referring to the drawings, forming a part

of this specification, Figure 1 is a side elevation of an ordinary hot air furnace unit or heating system equipped with the improved air circulating and distributing device as constructed and used as an attachment.

Fig. 2, a top plan view of the same.

Fig. 3, a fragmentary sectional view of a modification incorporated in or forming a component part of the upper or dome portion of an ordinary furnace casing.

Similar numerals of reference designate like parts throughout all the figures of the drawings.

The heating unit or furnace 1, may be of any suitable and convenient construction and so likewise the surrounding casing 2, the latter, in the present instance, being provided with the usual distributor dome 2^a and the usual hot air distributing pipes or conduits 3.

The air to be heated may be conducted to the base portions of the casing 2 in any suitable and convenient manner, as for example,—by means of air supply pipes or conduits 4. The supply pipes or conduits 4 may communicate with any suitable source of supply, as for example,—fresh air exterior to the building to be heated or communicating with suitable return pipes leading from the base portions of the rooms heated by the distributing pipes or conduits 3.

As a means of providing for a forced circulation and distribution of air in connection with a furnace structure of conventional form, a manifold 5 is provided, said manifold 5 being provided with hot air or heat distributing conduits 6 and communicating with the top or dome portion of the casing 2. The manifold 5 provides a hot air or heat accumulating and equalizing chamber 5^a above the motor driven air circulating device 7. The air circulating device 7 is preferably in the specific form of a blower fan, as indicated in Fig. 1 of the drawings, said fan 7 being mounted on a vertically arranged shaft 8. The fan shaft 8 extends through the manifold 5 so that the motor 9 may be arranged on the exterior of the

manifold casing, as shown. The motor is adapted to be mounted and secured in a suitable supporting frame 10, and when the motor driven blower is to be installed in connection with a furnace structure already in use, the manifold 5 is preferably provided with a depending pipe section 5' extending downwardly within the central portion of the dome or casing preferably opening just above the heating unit 1 to draw the air from the sides of the latter as received from the supply pipes 4. In the forms shown in Figs. 1 and 2 and in Fig. 3 of the drawings the lower end of the fan shaft is mounted in a bearing 11^a of a suitable bearing bracket 11 arranged within the lower end of the manifold conduit section 5'.

In the forms shown in the drawings the top of the manifold is in the specific form of an inverted cone forming a deflector 5^b against which the air is adapted to pass from the air circulating device or blower fan 7 and being adapted to divide and equalize the air within the chamber 5^a preparatory to being passed through the distributing pipes 6. It will be seen also that the pipes 6 intersect the base portions of the main distributing pipes or conduits 3 and it will also be apparent that when the air circulating device 7 is thrown out of operation or is at rest the furnace will be permitted to function in the ordinary manner.

In the form shown in Fig. 3 of the drawings the air distributing pipes 3 are dispensed with, the heat accumulating and distributing chamber 5^a leading directly to a single set of air distributed conduits or pipes 6^a for use in lieu of the pipes or conduits 3 and 6, shown in Figs. 1 and 2 of the drawings. In this form the air circulating device is in the specific form of an ordinary fan 7^a instead of a fan of the blower type as shown in Fig. 1 of the drawings.

Having thus described some of the embodiments of my invention, without having attempted to set forth all the forms in which it may be made, or all the modes of its use, what I claim and desire to secure by Letters Patent is,—

1. In a heating apparatus, a furnace, a casing surrounding the same, means for supplying the air to be heated to said casing, means for mechanically causing a circulation of air through said casing and over said furnace, a manifold provided with hot air distributing pipes and having a hot air accumulating and equalizing chamber, and means for driving said mechanical air circulating means from the exterior of said manifold.

2. In a heating apparatus, a casing, a heating unit arranged therein, an air supply conduit leading to said casing, a mani-

fold forming a heat accumulating and equalizing chamber above said heating unit, 65 heat distributor pipes leading from said manifold, and motor driven means below said chamber for creating a forced draught of heated air through said supply conduit and distributor pipes and accumulating the 70 same within said chamber.

3. In a heating apparatus, the combination with a casing, and a heating unit arranged within the casing, and air conduits leading to said casing; of a communicating manifold forming a hot air accumulating and equalizing chamber above said heating unit, hot air distributing pipes leading from said manifold, and means above said heating unit and below said chamber for creating a forced draught through said distributing pipes and accumulating hot air within 80 equalizing chamber.

4. In an apparatus of the class described, a heating unit, a casing surrounding the 85 same and provided at its base with air supply conduits, a casing dome above said heating unit provided with heat distributing conduits, a manifold provided with an air accumulating and equalizing chamber 90 and having heat distributing pipes intersecting said distributing conduits, a mechanical blower below said chamber, and a motor exterior to said manifold for driving said mechanical blower.

5. In an apparatus of the character described, a heating unit, a surrounding casing including a source of air supply at its base portion, a manifold provided with an inverted cone shaped deflector and an annular heat accumulating and equalizing chamber arranged above said heating unit and communicating with said casing, heat distributing conduits leading from said manifold and chamber, an air circulating device between said heating unit and said chamber of said manifold, and a motor above and exterior of said manifold for driving said air circulating device.

6. In an apparatus of the character described, a heating unit, a casing surrounding the same and provided with a hot air accumulating dome, a source of air supply leading to said casing, hot air distributing conduits leading from said dome, a manifold arranged above and communicating with said dome and provided with a hot air accumulating and equalizing chamber, a motor driven air circulating device between the latter and said chamber, and radially extending hot air distributing conduits leading from said manifold into said hot air distributing pipes.

7. In an apparatus of the character described, a heating unit, a surrounding casing provided with a hot air accumulating

dome, a source of air supply for said casing, hot air distributing conduits leading from said dome, a hot air equalizing manifold including a deflector arranged above and communicating with said dome, an air circulating device between the latter and said manifold, a driving shaft leading from said air circulating device to the exterior of said

manifold, a motor on said manifold connected to said shaft, and heat distributing conduits leading from said chamber to said heat distributing conduits leading from said dome.

In testimony whereof I have affixed my signature.

ARTHUR H. ROBINSON.
